UNITED STATES PATENT OFFICE

2,487,624

SAFETY CULINARY KNIFE

Edna M. Wiggers, Jackson Heights, N. Y., assignor
of fifty per cent to Catherine Lodes, Yonkers,
N. Y.

Application December 13, 1945, Serial No. 634,772

1 Claim. (Cl. 30—278)

1

This invention relates to knives, and more particularly to a safety paring knife having means for detachably receiving one-half of a split safety razor blade which is held flat against the guard member of the knife by means of a resilient clamping arm pivoted to said guard.

One object of the present invention is to provide a safety culinary knife of the above nature in which the guard has a sharp curved side edge for cutting vegetables and fruits.

A further object is to provide a culinary knife of the above nature on which the pivoted clamping arm is formed with a resilient bent end section which serves to hold the blade tightly in operating position when the end of said arm is flexed under a catch member on said guard.

A further object is to provide a culinary knife of the above nature in which said guard is provided with a pair of upstanding pins which serve as stop members to insure the swinging of said arm into its proper clamping position.

A further object of the above invention is to provide a device of the above nature which will be simple in construction, inexpensive to manufacture, easy to install and manipulate, ornamental in appearance, and very efficient and durable in use.

With these and other objects in view, there has been illustrated on the accompanying drawing one form in which the invention may conveniently be embodied in practice.

In the drawings,

Fig. 1 represents a top plan view of the safety culinary knife.

Fig. 2 is a side view of the same.

Fig. 3 is a cross sectional view of the same, taken along the line 3—3 of Fig. 1.

Fig. 4 is a similar cross sectional view of the same, taken along the line 4—4 of Fig. 1.

It has been found from experience that the ideal cutting edge of a knife for use in the paring, peeling, scraping, and slicing of vegetables and fruits is provided by a safety razor blade. The ordinary safety razor blade, however, is so wide that it cannot be used in a narrow culinary knife, but the best results are obtained with one-half of a standard safety razor blade which has been split longitudinally, thus permitting the culinary knife to be relatively narrow and easy to operate.

Referring now to the drawings in which like reference numerals denote corresponding parts throughout the several views, the numeral 10 indicates a cylindrical handle preferably disposed in a horizontal position, as clearly shown in Fig. 2. The handle 10 has a reduced neck surrounded by

2

a ferrule 11, and said handle also has an inferior flat recess 11a for receiving a laterally bent over rear end 13 of a guard member 12, said rear end 13 being securely imbedded in said recess and preferably secured therein, as by the use of cement. The guard member 12 is provided with a flat main body section 13a from which extend a pair of upstanding pins 14, 15, adjacent a straight flat side edge 16 thereof. The edge of the guard member opposite from the pins 14, 15 is curled downwardly, as clearly shown in Fig. 3, as indicated by the numeral 17, and said edge 17 is sharpened and extended forwardly beyond the body section 13a to provide a pointed V-shaped cutting extremity 18 which may be used for coring vegetables or fruits.

The flat side edge 16 of the guard member 12 is provided at its rear end with a raised inturned catch member 19 made integral with the body section 13a. The guard member 12 is provided with a longitudinal slot 20 having a beveled edge 21, which slot serves to permit the peelings and slicings cut from the fruit or vegetables by a split razor blade section 22 to pass through said slot 20. The slot 20 is preferably parallel to edge 17 of the guard member 12.

In use, the razor blade section 22 is adapted to lie flat upon the body 13a, and has a sharp edge 23 held tightly in spaced position with respect to the beveled edge 21 by means of a swinging clamping arm 24.

The clamping arm 24 is provided on its rear extremity with an upcurved resilient end 25 which is adapted to be flexed downwardly against the guard 12 and pushed under the catch 19 previously described—said catch thus serving to hold said clamping arm tightly in flat frictional engagement with the razor blade 22.

The clamping arm 24 is connected to the forward end of the guard by means of a pivot pin 26, preferably made in the form of a tubular rivet. The clamping arm 24 is also provided with a pair of side notches 27, 28 which are adapted to embrace the pins 14, 15 and thus hold said arm 24 in proper operating position when it is swung against said pins.

One advantage of the present invention is that the knife never needs to be resharpened, as it is merely necessary to remove the safety razor blade section when it becomes dull and replace it with a new one.

While there has been disclosed in this specification one form in which the invention may be embodied, it is to be understood that this form is shown for the purpose of illustration only, and

that the invention is not to be limited to the specific disclosure, but may be modified and embodied in various other forms without departing from its spirit. In short, the invention includes all the modifications and embodiments coming within scope of the following claim.

Having thus fully described the invention, what is claimed as new, and for which it is desired to secure Letters Patent, is:

In a culinary knife, a handle having a guard secured thereto, said guard being longitudinally straight and transversely curved and having an elongated slot formed therein parallel to the edge thereof, a detachable narrow razor blade member mounted on the convex side of said guard and having a sharp cutting edge aligned with said slot, a resilient clamping arm pivoted to the outer end of said guard at one end and upwardly concave at the opposite end, and means on said guard to hold said opposite end of the clamping arm tightly in flat condition to clamp said razor blade

member against said guard, a pair of upstanding stop pins being provided on the rear edge of said guard parallel with said slot, and said clamping arm having a pair of notches to embrace said upstanding stop pins.
